CHARLES H. KIMBLE, JR., OF SPOKANE, WASHINGTON, ASSIGNOR TO C. W. HILL PRINTING COMPANY, OF SPOKANE, WASHINGTON

CHANGEABLE EXHIBITOR

Application filed December 15, 1930. Serial No. 502,457.

My present invention relates to an improved changeable exhibitor of the folded leaves type, that is hand operated, for the purpose of displaying, successively, a series of views, pictures, advertising features and similar subject matter, the leaves forming a foldable strip which may be re-folded after it has been exhibited or unfolded. In carrying out my invention the folded leaves are fashioned by folding a strip of paper or other similar flexible material, as in the form of an accordion fold, and the folded strip is enclosed in an envelope of heavy paper or other flexible material suitable for the purpose, and provided with a closure and fastener, in order that the envelope may be closed and fastened while the strip is being unfolded and exhibited, and readily opened for the purpose of re-folding and re-inclosing the strip in the envelope for subsequent exhibition.

The front wall of the envelope is provided with an open slot through which the successive leaves may be drawn, and the first leaf of the folded strip is fashioned with a pull-tab or tongue to be grasped between the fingers and thumb for successively unfolding and withdrawing the confined folded strip from the envelope, as will hereinafter be more fully described.

The invention consists in certain novel combinations and arrangements of parts as will be set forth and claimed. In the accompanying drawings I have illustrated one complete example of the physical embodiment of my invention wherein the parts are combined and arranged according to one mode I have thus far devised for the practical application of the principles of my invention.

Figure 1 is a face view of the changeable exhibitor embodying my invention.

Figure 2 is a view similar to Figure 1, but with the strip partially withdrawn from the envelope.

Figure 3 is a perspective view of the exhibitor, showing the envelope partly open to disclose the interior arrangement of the device.

Figure 4 is a perspective view on a reduced

scale, with the parts in the position of Figure 2.

In the present exemplification of the invention I have shown the changeable exhibitor as an advertising display device, depicting a store front, on the front wall of the envelope, with front windows through which the pictures on the advertising strip may be observed, said pictures preferably showing various goods, merchandise, and commodities sold in the store of the proprietor using the advertising exhibitor.

The envelope, which is fashioned from suitable heavy paper or other material, is provided with a front wall 1, on the outer face of which the store front is depicted, and a rear or back wall 2, between which walls a bend or bottom fold 3 is fashioned so that the two walls may lie flat when the envelope is closed. For closing and fastening the envelope I provide the front wall with an inwardly bent or folded tongue 4 of suitable length and width, and the rear or back wall 2 is fashioned with a complementary, transverse slit 5 near its upper free end. The tongue is folded over the back face of the back wall and tucked into the slit 5 to close and fasten the envelope, leaving its two sides open.

The front wall 1 of the envelope is provided with two spaced openings or windows 6 and 7 that conform to the picture of the store-front depicted on the face of the front wall of the envelope, and these two spaced openings that are cut into the material of the wall may be provided with transparent panes of suitable material pasted, glued, or in other manner secured to the back face of the front wall.

Near the bottom of the front wall a slot 8 is provided that extends along the folded or lower edge of the envelope, below the two spaced windows, and this slot is of sufficient length to permit the folded strip to slip therethrough, a pull-tab 9 on the end of the strip being passed through the slot from the inside of the envelope.

The strip is fashioned of tough paper or other suitable material, and it is folded into alternate leaves or pages 10, and 11, the num-

ber employed depending upon the length of the strip. The leaves 10 are provided with spaced pictures, views and other subjects-matter, while the leaves 11 are usually blank.

5 As shown in Figure 2 the two pictures or pairs of shoes on a leaf 10 are spaced equidistant with the windows 6 and 7 of the front wall of the envelope, in order that the leaf 10, before it is pulled from the envelope, will 10 disclose the spaced pictures in the store windows for display and advertising purposes.

The first leaf 10, as shown, may bear a suitable advertisement identifying the store pictured on the envelope, and the pull-tab 9 15 bears the instructions to "pull straight down" for the purpose of operating the display device.

The last sheet or leaf of the strip, as 12, is pasted, glued, or otherwise secured to the 20 inner face of the back wall of the envelope, as indicated in Figure 3.

The series of leaves 10, thus have two rows of pictures arranged thereon, alined with the windows of the store front, and assuming the 25 exhibitor to be in the position of Figure 1, the tab 9 may be pulled to displace the two pictures appearing on the first leaf. After the first pictured leaf has been pulled through the slot 8 the first blank leaf follows, leaving 30 the second pictured leaf behind the store front and windows, and the succeeding pictured leaves and blank leaves are drawn from the envelope until the anchor leaf 12 discloses its pictures through the windows 6 and 7.

35 To re-fold and enclose the strip in the envelope, the tongue 4 is pulled from its slit 5 to permit opening of the envelope, after which the strip is pulled back through the slot 8 into the interior of the envelope, and the leaves are folded into place as the strip 40 is pulled back, until only the pull-tab 9 is left projecting through the slot 8. The envelope is then closed and fastened, and the exhibitor is ready for subsequent use.

45 While I have shown and described the exhibitor as a device for advertising merchandise sold in a store, it will be understood that the folder or envelope may have one of a variety of scenes depicted thereon, and the 50 pictures on the leaves 10 may be photographs, landscapes, marine views &c., arranged in two rows or series, and visible, successively through the windows of the front wall of the folder or envelope.

55 The folder or envelope lends itself readily for use in mail-advertising, the envelopes may be handed out for advertisements, or they may be distributed in other acceptable ways for advertising campaigns.

60 Having thus fully described my invention, what I claim as new and desire to secure by Letters Patent is:-

65 1. The combination with a two-piece envelope having a closure and fastening means therefor and provided with a window and a

slot in its front wall, of a strip of flexible material folded in a series of leaves one of which is anchored to the back wall of the envelope, a pull-tab on the strip passed through said slot, and said strip adapted to be pulled through said slot for successively displaying leaves back of the window. 70

2. The combination with a hinged envelope having a closure and fastening means therefor and provided with a window and a slot in its front wall, of a strip of flexible material folded in a series of leaves, the back leaf of the strip being secured to the inner face of the back wall of the envelope, and a pull-tab on the free end of the front leaf passed through said slot from the inside of the envelope. 75

3. The combination with a hinged envelope having a closure and fastening means therefor, said envelope having in its front wall a pair of spaced windows and a slot beneath the windows, of a strip of flexible material folded in a series of leaves, alternate leaves of the series having thereon spaced pictures corresponding with the spaced windows, the back leaf of the series being secured to the inner face of the back wall of the envelope, and a pull-tab on the free end of the front leaf passed through said slot in the front wall of the envelope. 80 85 90 95

In testimony whereof I affix my signature.
